MECHANICAL MOVEMENT: TOY MACHINE

Edward S. Peake, Westerville, Ohio, assignor to
The Kilgore Manufacturing Company, Wester-
ville, Ohio, a corporation of Ohio

Application March 22, 1932. Serial No. 600,465

28 Claims. (Cl. 42—57)

My invention relates to firearms and, in particular, to toy fire arms.

It is the object of my invention to provide a machine gun type of firearm which is actuated by a crank in order to provide continuous firing, preferably from a strip of ammunition.

In particular, it is the object of my invention to provide such a firearm by which the strip carrying the ammunition is fed to firing position while the hammer is held inoperative; after feeding to firing position the strip is held against retraction; while the hammer is cocked and held cocked, and, after the strip is clamped, the hammer is released to fire the strip which is still held until the strip is released and again fed in a new cycle of operations. The holding of the strip is continuous until released by the feeding mechanism, thus preventing its retraction of the strip at any time and preventing its forward movement except when being positively so fed.

It is a further object to provide means of stripping the strip, both from its feeding means and from the firing hammer so as to insure its free ejection after having been fired.

It is a further object to provide a novel form of inspection door and means of mounting it so as to facilitate the loading and unloading and inspection of the weapon.

It is a further object to provide positive means of feeding the ammunition carrying strip so arranged that only the ammunition carrying strip, which will fit the weapon, can be used, in order to insure uniformity of operation and accuracy of firing for safety.

In particular, it is my object to provide a spring-pressed, rotating, firing disk adapted to clamp the ammunition carrying strip against retrogression, a spring-pressure hammer and a common operating means for the feeding means and the hammer means successively operated and so interlocked as to prevent retrogression of the strip, the premature firing of the strip and to insure a rigid holding of the strip except when being positively fed.

It is a further object to provide a spring-pressed moving anvil which acts as a support for the ammunition strip and also as a means for clamping the ammunition strip as well as receiving the blow from the spring-pressed hammer. This moving anvil performs the several functions of supporting, feeding, clamping and receiving the blow yieldingly that is given to the ammunition strip.

It is a further object to provide a handle which, when once interlocked with the weapon, cannot

be detached without such positive movement as to prevent any premature firing.

Referring to the drawings:

Figure 1 is a side elevation of the weapon from the loading side of the weapon; 60

Figure 2 is a front elevation thereof;

Figure 3 shows the firing mechanism in position in which the strip is being held after firing just prior to being released and fed to a new position; 65

Figure 4 indicates the parts in feeding position;

Figure 5 shows the parts just after the strip has been fed and reclamped;

Figure 6 shows the firing of the strip; 70

Figure 7 is a top plan view of the weapon with the loading door open showing the spreading of half of the weapon, which spreading acts as a spring resistance for the hinge of the door; 75

Figure 8 is a section on the line 8—8 of Figure 3;

Figure 9 is a section on the line 9—9 of Figure 1 showing the door in open position and the details of the door hinge; 80

Figure 10 is an inside elevation of the door;

Figure 11 is a detail side elevation of the actuating cams;

Figure 12 is a detail side elevation of the reverse side of the operating cams; 85

Figure 13 is a section on the line 13—13 of Figure 11 showing the cam operating mechanism;

Figure 14 is a section on the line 14—14 of Figure 3 showing the arrangement of the stripping shoulders to insure the removal of the firing strip from the feeding disk and the firing hammer; 90

Figure 15 is a modification of the firing disk showing its tooth feeding arrangement for feeding the ammunition strip positively; 95

Figure 16 is a detail section between the feeding disk and the clamping pin on the line 16—16 of Figure 3;

Figure 17 is a perspective of the crank and the interlocking sleeve carrying the operating cams, which sleeve is engaged by the crank shaft; 100

Figure 18 is a plan view of the ammunition strip;

Figure 19 is a plan view of the ammunition strip having registering feeding apertures for mounting on the feeding pins of the feeding disk.

Referring to the drawings in detail, the weapon is comprised of a right hand half 110

on which is mounted the operating crank 2 and the left hand half 3 on which is mounted the loading door 4. The right hand side is known as the operating side and the left hand side is known as the loading side. The crank 2 is provided with a shaft 5 having a lug 6 which is insertible through a slot 7 in the sleeve 8 and then rotated in a groove 9 within this sleeve until the projection 6 engages the shoulder 10 on the sleeve, thereby rotating the sleeve which carries the cam members 11 and 12.

Associated with the cam members is a feeding shoulder 12a having a serrated face 13 which may be employed to assist in feeding the ammunition strip. The sleeve 8 and the cams and shoulders thereon are so constructed that when the handle is withdrawn firing can not take place, and the ammunition strip will be held against movement.

20 The ammunition strip is designated 14, the roll of which is mounted upon the supporting pin 15 from which the strip 16 is fed. The strip 16 is provided with spaced ammunition firing members 17. The strip then passes over the feeding disk 18 which is freely supported upon the axle 19 which axle is carried on the swinging, spring-pressed arm 20 that is pivoted at 21 and is impelled forwardly by the spring 22 wound upon the pivot support 21 having one arm 23 engaging the abutment 24 on the pistol casing and the other arm 25 engaging the hook 26 on the swinging arm 20. The cap strip having proceeded between the face of the disk 18 and the tapered abutment 27 proceeds upwardly 30 between the hammer stripping shoulders 28 and over the feeding disk stripping shoulders 29 out through the apertures 30 which is the ejection aperture at the top of the weapon. When in clamping position, the disk 18 rests upon the tapered abutment 27. The disk itself has a tapered face which facilitates this operation.

As the cam members 11 and 12 are operated, they engage the surface of the strip 16 where it rests upon the disk 18 and lift the disk against the resistance of its spring 22 causing the disk to rotate and the strip 16 to feed forwardly. At this time the opposite cam prevents the hammer 31 having a hammer face 32 from moving to firing position under the impulse of its spring 33 wound on its pivot support 34, such spring having one arm 35 engaging the abutment 36 and the other arm 37 engaging the hook 37 on the hammer 31. This hammer is provided with a cam surface 38 for engaging with the rotating cam so that the cam will hold the hammer in inoperative position during the period desired. Upon the completion of the feeding operation, the disk 18 drops back upon the abutment 27 clamping the ammunition strip between the disk and the abutment against further movement. Thereafter, the cam engaging the hammer releases the hammer which proceeds to apply its firing face 32 under the impulse of the spring 33 against the powder spot 17 in the strip 16 causing the powder to explode. As the crank continues to operate a new feeding operation takes place ejecting the fired portion of the strip and presenting a new ammunition spot 17 into firing position, as heretofore described.

70 The ammunition strip is prevented from sticking to the face 32 of the hammer 31 by the shoulders 28 and is prevented from sticking to the disk 18 by the shoulders 29, such shoulders being spaced apart to permit the disk and hammer to reciprocate back and forth between the shoulders to effect the stripping operation.

It will be noted that the strip is intermittently fed and, when not being fed, is positively held against retrogression or progression.

In order to provide access to the interior of the weapon, the door 4 with the thumb piece 39 is provided with a pair of vertically-extending hinge members 40 which are engaged between the angular-faced shoulders 41 on the half of the weapon marked 1 and a flat face abutment 42 having end shoulders 43 for engaging the arcuate face 44 of the upward projecting members 40. Thus, when the door is swung open, it will tend, by reason of the cam construction of the upwardly projecting members 40, to force this support and engaging shoulders 41 and 42 apart. This results in springing the rear ends of the halves 1 and 3 apart.

This spring resistance acts as a spring to hold the door either in open or closed position. The resiliency of the metal comprising the halves 1 and 3 provides this sufficient spring action because the halves are connected together only at their forward ends by the screws or bolts 45. The halves are connected together adjacent the bottom of the weapon through the halves of the 100 weapon comprising the butt as at 46. The door is thus provided with a hinge comprising cam members engaging with cam shoulders on the respective halves of the body of the weapon.

As the door is moved so that the cams pass 105 over dead center the halves of the weapon at the rear are sprung apart and yieldingly resist this movement and yieldingly retain the door either in its open position or its closed position.

As will be seen in Figures 15 and 19, the feeding disk 18 may be provided with feeding pins 18a engaging the apertures 18b of the strip 16 so as to insure positive feeding of the strip.

These pins accurately fit the apertures in the strip so that unauthorized ammunition cannot 115 be used in the weapon, thus insuring the safe and satisfactory operation of the weapon with ammunition designed for it.

One of the advantages of my invention is to provide a spring-pressed, rotating disk which acts 120 as a yielding anvil while at the same time acts as a feeding member which will yieldingly accommodate itself to different thicknesses of strip so that the parts are self-adjusting for both feeding and firing and also absorb the shock of firing. 125 It also acts as a strip clamp.

In a weapon of this character it is necessary to make the parts simple, strong and effective. This invention provides automatic operation, continuous firing, absolute safety, together with meeting 130 the requirements of cheapness, which is difficult to satisfy in weapons having continuous, automatic safe firing operations.

It will be understood that I desire to comprehend within my invention such modifications as 135 may be necessary to adapt it to varying conditions and uses.

Having thus fully described my invention, what I claim as new and desire to secure by Letters Patent is:

1. In a weapon, means to hold an ammunition strip, a sleeve having thereon means to periodically engage said holding means and ammunition strip to move the strip, firing means adapted to engage said ammunition strip and holding means while not moving, and means on the second-named means for rendering said firing means inoperative while the ammunition strip is being fed.

2. In a weapon having a continuous strip of

- spaced ammunition members, means for holding said ammunition strip against movement, a sleeve having thereon means for engaging said ammunition strip and the holding means for feeding the strip forward, means of firing the ammunition strip, and means on the second-named means for holding the firing means inoperative during the feeding operation. 5
3. In a weapon having a continuous strip with spaced ammunition members therein, a rotating feeding and clamping mandrel, a cooperating clamping member to clamp the strip between it and the mandrel, a feeding means for lifting said mandrel and moving it with the strip and a firing means. 10
4. In a weapon having a continuous strip with spaced ammunition members therein, a rotating feeding and clamping mandrel, a cooperating clamping member to clamp the strip between it and the mandrel, a feeding means for lifting said mandrel and moving it with the strip, a firing means, and means of rendering said firing means inoperative while said strip is being fed, said strip being held against movement while being fired. 15
5. In a weapon having a continuous strip of spaced ammunition members, a yielding feeding and clamping means, a positive feeding means adapted to disengage the clamping means from clamping position while feeding, a firing means, and means operated by the firing means to render it inoperative during feeding. 20
6. In a weapon having a continuous strip of spaced ammunition members, a feeding disk rotatably and yieldingly supported, a clamping abutment adapted to engage the strip between the disk and the abutment, a feeding finger adapted to lift the disk, rotate it and feed the strip thereon and then lower the disk and strip into engagement with the abutment, a firing hammer, and means associated with the feeding finger for maintaining the firing hammer inoperative during feeding. 25
7. In a weapon having a continuous strip of spaced ammunition members, a common operating means, a rotatably and yieldingly supported feeding disk on which the strip is mounted, an abutment between which and the disk the strip is clamped, a firing hammer adapted to rest upon the disk and the strip, yielding means for impelling the hammer into strip-engaging position, a feeding means associated with the common operating means for lifting the disk from its clamping abutment and feeding the strip and simultaneously lifting the firing hammer from the strip, holding it off of the strip, and permitting it to engage the strip after the completion of the feeding operation and the reengagement of the strip between the feeding disk and abutment. 30
8. In a weapon having a continuous strip of spaced ammunition members, a common operating means, a rotatably and yieldingly supported feeding disk on which the strip is mounted, an abutment between which and the disk the strip is clamped, a firing hammer adapted to rest upon the disk and the strip, yielding means for impelling the hammer into strip-engaging position, a feeding means associated with the common operating means for lifting the disk from its clamping abutment and feeding the strip and simultaneously lifting the firing hammer from the strip, holding it off of the strip, and permitting it to engage the strip after the completion of the feeding operation and the reengagement of the strip between the feeding disk and abutment, and
- stripping means for stripping said strip from the feeding disk. 35
9. In a weapon having a continuous strip of spaced ammunition members, a common operating means, a rotatably and yieldingly supported feeding disk on which the strip is mounted, an abutment between which and the disk the strip is clamped, a firing hammer adapted to rest upon the disk and the strip, yielding means for impelling the hammer into strip-engaging position, a feeding means associated with the common operating means for lifting the disk from its clamping abutment and feeding the strip and simultaneously lifting the firing hammer from the strip, holding it off of the strip, and permitting it to engage the strip after the completion of the feeding operation and the reengagement of the strip between the feeding disk and abutment, stripping means for stripping said strip from the feeding disk, and stripping means for stripping said strip from the firing hammer. 40
10. In a weapon having a continuous strip of spaced ammunition members, means to support a roll of the strip, a spring-pressed arm pivoted in the weapon, a disk freely mounted rotatable thereon adapted to carry the strip on its periphery, an abutment associated in spaced relationship to the disk between which and the disk the strip is clamped, a spring-pressed hammer having a cam face and a firing face, a handle adapted to rotate, actuating fingers, one of which is adapted to lift the disk and strip from the abutment and feed the strip with the disk while lifting the hammer and holding the hammer in elevated position until the strip is fed and reclamped, whereupon the hammer is allowed to engage this strip and disk, and yielding means to cause said engagement. 45
11. In combination in a weapon having a continuous strip of spaced ammunition members, the combination of means for clamping the ammunition strip, a sleeve having thereon means for releasing the clamping means and feeding the ammunition strip, means for reclamping the feeding strip, and means operated by the second-named means for firing the ammunition strip. 50
12. In a weapon, having a continuous strip of spaced ammunition members, a yielding movable feeding anvil, a firing means, and means for supplying an ammunition strip therebetween. 55
13. In a weapon having a continuous strip of spaced ammunition members, a yielding rotatable feeding anvil, a firing means, means for supplying an ammunition strip therebetween, a holding means for holding the strip on the anvil against movement. 60
14. In a weapon having a continuous strip of spaced ammunition members, a yielding feeding anvil, a firing means, means for supplying an ammunition strip therebetween, a holding means for holding the strip on the anvil against movement, and means for successively releasing the strip, feeding the strip and releasing the firing means to engage the strip after the strip is released and reheld. 65
15. In a weapon having a continuous strip of spaced ammunition members, a rotatable anvil, means to clamp the strip on the anvil, a firing hammer, means to retract the hammer, releasing the strip and feeding it and thereafter permitting the reengagement of the strip to hold it and to release the hammer to firing position. 70
16. In a weapon having a continuous strip of spaced ammunition members, a rotatable anvil, means to clamp the strip on the anvil, a firing

- hammer, means to retract the hammer, releasing the strip and feeding it and thereafter permitting the reengagement of the strip to hold it and to release the hammer to firing position, and means to yieldingly impel the anvil into strip clamping position and to yieldingly hold the strip between it and the strip feeding means while feeding is taking place.
17. In a weapon having a continuous strip of spaced ammunition members, a rotatable anvil, means to clamp the strip on the anvil, a firing hammer, means to retract the hammer, releasing the strip and feeding it and thereafter permitting the reengagement of the strip to hold it and to release the hammer to firing position, and means to yieldingly impel the anvil into strip clamping position and to yieldingly hold the strip between it and the strip feeding means while feeding is taking place, and means to strip the strip from both the firing means and the anvil after firing.
18. In a weapon having a continuous strip of spaced ammunition members, a casing, a handle mounted on said casing projecting into the interior thereof, means of supporting a supply of ammunition strip, a feeding and clamping means engaging said strip and directing it out of the casing, a firing hammer, and means operated by said handle for engaging said strip and moving it to firing position, cocking the hammer, releasing the strip so that it may be reengaged and releasing the hammer.
19. In a weapon having a continuous strip of spaced ammunition members, a casing, a handle mounted on said casing projecting into the interior thereof, means of supporting a supply of ammunition strip, a feeding and clamping means engaging said strip, and directing it out of the casing, a firing hammer, and means operated by said handle for engaging said strip and moving it to firing position, cocking the hammer, releasing the strip so that it may be reengaged and releasing the hammer, and a bayonet joint between said handle and said last mentioned means, whereby said handle may be detachably locked thereto and unlocked therefrom.
20. In a weapon having a continuous strip of spaced ammunition members, a detachable handle, a casing, means including a rotatable anvil for clamping, feeding, reclamping and firing an ammunition strip carried in said casing and ejecting said strip therefrom operable by said handle, said means being so arranged that, when the handle is detached, firing cannot take place but said ammunition strip will be held against movement and the hammer will be positioned in inoperative position for firing.
21. In a weapon having a continuous strip having spaced ammunition members, a handle having rotary movement for continuous actuation of the feeding and firing mechanism, feeding means including a rotatable anvil, a clamping means and firing means actuated by said handle.
22. In a weapon having a continuous strip, spaced ammunition members, a handle having rotary movement for continuous actuation of the feeding and firing mechanism, feeding means, clamping means and firing means actuated by said handle, and means associated with said handle for controlling the successive operations of unclamping the strip, feeding it, permitting it to be reclamped, cocking the firing means, holding it in cocked position and releasing it for firing.
23. In a weapon, means to support a roll of ammunition, a hammer, a swinging roller for guiding the ammunition, and a rotatable member for operating the hammer cooperating with the swinging roller for feeding the ammunition.
24. In a weapon, means to support a roll of ammunition, a hammer, an oscillatory roller for guiding the ammunition, and a rotatable member having cams thereon for operating the hammer and for feeding the ammunition.
25. In a weapon, a casing having in one side a cavity and a pin in the cavity, an arm located in the cavity and pivoted at one end to the pin, a roller on the other end of the arm for guiding a strip of ammunition, and a rotatable member having means thereon cooperating with the roller to feed the strip and after the feeding of the strip to cause an impact upon the strip.
26. In a weapon, a casing having in one side a cavity and a pin in the cavity, an arm located in the cavity and pivoted at one end to the pin, a roller on the other end of the arm for guiding a strip of ammunition, and a rotatable member having a pair of cams thereon cooperating with the roller to feed the strip and after the feeding of the strip to cause an impact upon the strip.
27. In a weapon, a casing having in one side a cavity and a pin in the cavity, an arm in the cavity pivoted at one end to the pin, a roller on the other end of the arm for guiding a strip of ammunition, means to produce impacts upon the strip, and a rotatable member having a projection thereon cooperating with the roller to feed the strip and after the strip is fed operating said means to produce an impact upon the strip.
28. In a weapon, a casing having in one side a cavity and a pin in the cavity, an arm in the cavity pivoted at one end to the pin, a roller on the other end of the arm for guiding a strip of ammunition, means to produce impacts upon the strip, and a rotatable member having thereon a pair of projections, one projection cooperating with the roller to feed the strip while the other projection is operating on the impact producing means.
